CAN PUNCH AND POURING DEVICE

George C. Seville, San Francisco, Calif.

Application July 31, 1935, Serial No. 34,071

5 Claims. (Cl. 65—61)

My invention relates to improvements in can punch and pouring devices, and it consists of the combinations, constructions and arrangements hereinafter described and claimed.

5 An object of my invention is to provide a can punch and pouring device especially designed for use with canned milk. The device consists of a container which receives the can of milk, and the container has a cover hinged thereto which carries 10 puncturing elements for puncturing two openings in the can top when the cover is closed. One of the openings is made to the rear of the can top and is designed to admit air to the can as the milk is poured. This relieves any vacuum in 15 the can and permits a more rapid pouring of the milk. The other puncturing device also acts as a conduit and conveys the milk from the can to a pouring spout which is carried by the cover. The pouring spout is removable from the cover, and 20 this permits the parts to be thoroughly cleaned. A handle is provided for the container in order to aid in the pouring and if desired a stopper may be removably disposed at the outlet end of the spout.

25 If desired the wall of the container may be cut away to form windows through which the reading matter on the can may be viewed. This adapts the device to advertising purposes. The puncturing elements frictionally engage with the can top when the cover is closed and hold the cover against accidental swinging into open position. After the can has been emptied of its milk 30 the cover can be manually swung into open position, then the fingers may be inserted through the opening in the bottom of the container for lifting the can from the container.

35 The device is extremely simple in construction, and not only forms a ready means for puncturing a pouring opening and a vent opening in a can top, but also provides a means for housing the can. The device in use acts as a pitcher. Both the vent and the pouring spout can be closed, which makes the device sanitary.

40 Other objects and advantages will appear in the following specification, and the novel features of the device will be particularly pointed out in the appended claims.

45 My invention is illustrated in the accompanying drawing forming a part of this application, in which

Figure 1 is a transverse section through the device showing a can in position;

50 Figure 2 is a front elevation of the device with the can removed;

Figure 3 is a bottom plan view of the cover showing the pouring spout; and

Figure 4 is a section along the line 4—4 of Figure 3.

5 In carrying out my invention I provide a container which has a cylindrical wall 1 and a bottom 2. The wall 1 may be provided with openings or windows if desired, and in the present form of the invention I have shown three such windows 3 separated from each other by front 10 strips 4—4 and a rear strip 5. The windows 3 do not extend to the top of the container, nor do they extend to the bottom. The bottom 2 is provided with a large opening 6, and the fingers may be inserted through this opening when it is desired to remove the can 7 from the container. A handle 8 is secured to the container, and may be disposed in back of the strip 6 if desired. The top of the container is open, and a mouth piece 9 is formed at a point diametrically opposite the 15 handle 8.

20 A cover 10 is hinged to the container at 11, and is of the shape shown in Figure 3. This cover carries a removable spout 12 on its inner surface, see Figures 3 and 4. The spout may be of any 25 shape desired and I have illustrated the spout as being wedge-shaped with the widest portion of the wedge disposed at the outlet end of the spout. Figure 4 shows the spout 12 as being U-shaped in 30 cross section, and as having triangularly-shaped flanges 13 that ride in similarly shaped grooves 14 in the cover 10. It will be seen from this that the spout 12 may be slid into position, and will 35 frictionally hold itself to the cover when the spout is moved to its extreme position.

35 The spout carries a vent-forming tube 15 and a fluid-conveying tube 16. Figure 1 shows the tube 15 as being smaller in diameter than the tube 16. The purpose of this feature is to permit 40 the fluid from the can 7 to readily flow through the tube 16, and the size of the tube is such as to prevent the milk from forming a film across the tube and congealing so as to stop further passage of milk from the can. Both tubes 15 and 16 have cutting edges 17 and 18 respectively, and 45 these edges puncture the can top 19 at 20 and 21 when the cover 10 is moved into closed position. The tube 15 punctures the can top at the rear of the can, while the tube 16 punctures the top adjacent to the front of the can. This permits 50 all of the fluid in the can to be delivered through the tube 16, and also permits an immediate flow of air into the can through the tube 15 during each pouring operation.

55 It will be noted from Figure 1 that the rear 55

end of the spout 12 is open as at 22, and that the can top extends above the upper edges 23 of the windows 3. An air compartment is therefore formed by the can top 19, the cover 10, and the 5 container wall 1. Air can filter into this compartment between the can 7 and the inner surface of the container wall 1. This permits air to find its way through the opening 22 and into the can 7 as the milk is withdrawn, while still 10 closing the opening against the entrance of any insects. The outlet end of the spout 12 is made large enough to readily handle all of the fluid passing through the tube 16. This will prevent the fluid from backing up in the spout 12. A 15 washer 24 of rubber or leather is disposed on the tube 16 and seals the opening 21 in the can. The spout 12 has downwardly inclined portions 25 disposed adjacent to the tube 16, and this causes any fluid in the spout to gravitate back 20 into the can when the pouring operation is completed. The tubes 15 and 16 may be screwed or otherwise secured to the spout 12.

If desired a stopper 26 may be inserted in the outlet end of the spout, and this stopper may be 25 connected to the container by means of a chain 27. The spout 12 has an enlargement 28 designed to abut against the outer end of the mouth piece 9 to form a continuous and symmetrical appearance for the mouth piece. The windows 3 30 permit the writing on the can to be viewed and in this way the device acts as an advertising medium.

From the foregoing description of the various parts of the device, the operation thereof may 35 be readily understood.

The cover 10 is opened and the can is placed in the container 1. The cover is now swung into a position where the tube 15 rests on the can top 19. The cover is now manually moved into closed 40 position, and this will cause the tubes 15 and 16 to puncture the can top at the places designated. The stopper 26 may now be removed, and the device is ready for use. The device is handled in much the same manner as a pitcher, and the 45 cover is held against accidental opening by the engagement of the tubes 15 and 16 in the can top. After each use of the device the stopper 26 may again be inserted in the mouth piece 12. When the can is emptied the cover is swung into 50 open position, and then the can is removed from the container 1, this being accomplished by the person forcing his fingers through the opening 6, and pressing against the bottom of the can. A new can can be substituted for the empty one in 55 the manner already indicated.

While I have shown only the preferred form of my invention, it should be understood that various changes or modifications may be made within the scope of the appended claims without departing from the spirit of the invention.

I claim:

1. A can puncturing and pouring device com-

prising a can container with windows therein whose upper edges are spaced below the top of the can disposed in the container, a cover hinged to the container, the can top cooperating with the container wall and cover for providing a protected space against insects, a spout carried by the cover, a vent tube and a liquid conveying tube carried by the spout and designed to puncture the can top when the cover is swung into closed position, the end of the spout disposed within the 10 container, opening into the space defined by the can, the container and the cover, and a stopper 15 removably disposed in the outlet end of the spout, whereby both the vent and the outlet end of the spout are protected from insects.

2. A container designed to receive a can and having an inside diameter slightly larger than the diameter of a can receivable in the container; the wall of the container being provided with openings disposed below the can top; a cover for 20 the container; can puncturing members carried by the cover and constituting an air vent and a liquid outlet for the can; said cover, container wall, and can top constituting the sides of an air compartment; said air vent communicating with 25 the air compartment; whereby the air flowing into the can to take the place of the liquid poured out is shielded from insects and foreign matter.

3. A can puncturing and pouring device comprising a container for a can, a cover for the container, said cover having a channel on its inner surface tapered lengthwise, a trough having a similar lengthwise taper and being removably disposed in the channel for forming a liquid-tight seal along the edges of the trough, and a pair 30 of can cutting tubes carried by the trough, said trough and tubes being removable as a unit for cleaning purposes, the removal of the trough also permitting the channel to be cleaned.

4. A can puncturing and pouring device comprising a container for a can and provided with openings in its wall whose upper edges are spaced below the can top, a cover for the container and cooperating with the container wall and can top for providing a protected space from insects, a 45 spout tube and a vent tube carried by the container and designed to puncture the can top, the vent tube opening into the protected space in the container top, whereby the vent tube is protected from insects and foreign matter.

5. A can puncturing and pouring device comprising a container for a can, a cover for the container, said cover having a channel on its inner surface tapered lengthwise, a trough having a similar lengthwise taper, the edges of the channel 55 and the edges of the trough having cooperating ridges and grooves wedge-shaped in cross section for forming liquid tight connections between the parts, and a pair of can cutting tubes carried by the trough, said trough acting as a spout for conveying the liquid contents from the can.

GEORGE C. SEVILLE.
